(57) **CLAIM**

The ornamental design for an outlet for leash, as shown and described.

DESCRIPTION

FIG. 1 is a first perspective view of an outlet for leash showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing of portions of the outlet for leash in FIGS. 2 and 4 forms no part of the claimed design.

1 Claim, 7 Drawing Sheets
